US0D1055727S

(12) **United States Design Patent** (10) **Patent No.:** **US D1,055,727 S**
(45) **Date of Patent:** **** Dec. 31, 2024**

(54) **CAR CODE READER AND SCANNER TOOL**

(71) Applicant: **Jia Li**, Meizhou (CN)

(72) Inventor: **Jia Li**, Meizhou (CN)

(**) Term: **15 Years**

(21) Appl. No.: **29/924,496**

(22) Filed: **Jan. 19, 2024**

(51) LOC (14) Cl. **10-04**

(52) U.S. Cl.

USPC **D10/78**; D13/133

(57) **CLAIM**

The ornamental design for a car code reader and scanner tool, as shown and described.

DESCRIPTION

FIG. 1 is a top, front and right side perspective view of a car code reader and scanner tool showing my new design; FIG. 2 is a bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines show the portions of the car code reader and scanner tool that form no part of the claimed design.

1 Claim, 8 Drawing Sheets
